UNITED STATES PATENT OFFICE.

JOHN N. KAILOR AND ELMER L. WILLIAMS, OF COLUMBUS, INDIANA,
ASSIGNORS TO REEVES & CO., OF SAME PLACE.

CASING FOR CLOVER-HULLERS.

SPECIFICATION forming part of Letters Patent No. 473,259, dated April 19, 1892.

Application filed October 29, 1891. Serial No. 410,169. (No model.)

To all whom it may concern:

Be it known that we, JOHN N. KAILOR and ELMER L. WILLIAMS, citizens of the United States, residing at Columbus, in the county of Bartholomew and State of Indiana, have invented a new and useful Improvement in Casings for Clover-Hullers, of which the following is a specification.

Our invention relates to an improved casing for clover-hulling machines, more particularly that class of clover-hulling machines in which two operating-cylinders are used, one above the other.

The object of our improvement is to provide convenient means for obtaining access to and for removing the lower cylinder without disturbing the upper cylinder.

The accompanying drawings illustrate our invention.

Figure 1 represents a view in perspective of the frame of a clover-huller casing having our improvement. Fig. 2 represents a view in perspective of the front portion of a clover-huller having the casing opened for access to the lower cylinder.

In the drawings, A, B, C, and D are the corner-posts of the main frame, in which the cylinders are mounted. Said posts are connected in pairs by short beams E and F, which form bearings for the upper and lower cylinders, respectively, and are further connected at their lower ends by metallic plates G G, having arms I I, to which the bolster J is secured. The posts A and C and B and D are connected by suitable cross-beams L, M, N, and O, so as to form a rectangular main frame, to the rear side of which a secondary frame P is attached to receive the separating sieves and rakes.

The construction of the frame as thus far described forms the subject-matter of another application, now pending, by John N. Kailor, one of the parties hereto, and therefore need not here be more particularly described.

It will be understood that the lower hulling-cylinder R, Fig. 2, is mounted in bearings

on the beams F within the frame formed by the posts A, B, C, and D, and is therefore, when the casing is completed and ready for operation, completely inclosed. For the purpose of gaining convenient access to the lower cylinder to clean or remove it each of the posts A and C is cut at t and u, thus making a section of each removable above and in front of the lower cylinder.

The removable portions of the posts A and C are connected by a board V and provided with end pieces W W and a top covering X, so as to form a connected structure adapted to co-operate with the rest of the frame and casing and form a removable part thereof to inclose the upper front portion of the lower cylinder. This removable portion of the casing may be secured in position by hooks 2 2, attached to the main frame and engaging eyes secured to the removable section, as at 3, or in any other suitable manner. For the purpose of conveniently handling said removable portion of the casing a pair of arms 4 4 are rigidly secured at one end to opposite ends of the removable section, and the other ends of said arms are pivoted to the ends of the bolster J, so that the removable section may be conveniently swung out of position in the main casing, as illustrated in Fig. 2, thus forming a gap in the main frame and casing, through which access may be had to the lower cylinder R and through which said cylinder may be removed without disturbing the upper cylinder 5.

We claim as our invention—

1. In a clover-huller casing having bearings formed therein for two thrashing or hulling cylinders arranged one below the other, the combination of the main casing having in its front side, above the lower cylinder-bearings, an opening through which said cylinder may be inserted in or removed from its bearings, and the removable section adapted to fill said opening and to co-operate with the main casing to inclose said cylinder, substantially in the manner set forth.

2. In a clover-huller casing, the combina-

tion of the posts forming the corners of the main frame, the beams E and F, and plates G G, provided with arms I, connecting said posts in pairs, the bolster secured to said 5 arms, the removable casing adapted to fit into the main frame and to co-operate therewith to form an inclosed casing, and the arms rigidly secured to said removable casing and pivotally connected to the bolster, all substantially as set forth.

JOHN N. KAILOR.
ELMER L. WILLIAMS.
